No. 831,395.

PATENTED SEPT. 18, 1906.

S. J. & G. C. WELTER.

LUBRICATOR.

APPLICATION FILED APR. 6, 1905.

UNITED STATES PATENT OFFICE.

STUART JACKSON WELTER AND GROVER CLEVELAND WELTER, OF
ROSWELL, TERRITORY OF NEW MEXICO.

LUBRICATOR.

No. 831,895.

Specification of Letters Patent.

Patented Sept. 18, 1906.

Application filed April 6, 1905. Serial No. 254,099.

To all whom it may concern:

Be it known that we, STUART JACKSON WELTER and GROVER CLEVELAND WELTER, citizens of the United States, and residents of 5 Roswell, in the county of Chaves and Territory of New Mexico, have invented a new and Improved Lubricator, of which the following is a full, clear, and exact description.

Our invention relates to a device for lubricating wagon-axles successfully and doing away with the necessity of taking the wheel 10 from the axle when the oil is applied.

On account of the inconvenience of taking 15 wheels from axles it is well known that they are frequently left on so long as to become dry and to burn out the bearings.

It is the principal object of our invention to provide an oiling device which will be efficient, simple, and inexpensive, and yet which 20 can be filled with oil while a wheel is on the axle.

Reference is to be had to the accompanying drawings, forming a part of this specification, in which similar characters of reference 25 indicate corresponding parts in all the figures.

Figure 1 is a side elevation, partly in section, on the line 1-1 of Fig. 2, of a cast axle-skein, showing the principle of our invention. 30 Fig. 2 is a sectional view of the same on the line 2-2 of Fig. 1. Fig. 3 is a sectional view similar to Fig. 2, showing a way of applying the invention to a steel skein. Fig. 4 is a side elevation of the device shown in Fig. 3. 35 Figs. 5 and 6 are sectional views on the lines 5-5 and 6-6, respectively, of Figs. 1 and 3; and Fig. 7 is a perspective view of the oiling attachment shown in Fig. 1.

Referring first to Figs. 1, 2, 5, and 7, the 40 axle-skein *a* is constructed of cast metal, its main portion being made in the ordinary manner. Its bearing-surface *a'* is provided with a depression *a''*, and from this depression a channel *a'''* extends to a receptacle *b*, which is preferably cast in one piece with the skein. 45 This receptacle is provided with a passage *b'*, into which is designed to pass the main body of the oiling device proper, (represented by the letter *c*.) The oiler has a sliding tube *d* upon its outer surface, and this tube is 50 provided with a slot *d'*, which receives a lug *c'* upon the body of the oiler. At the rear of the slot *d'* is a shoulder *d''*, which is adapted to come into contact with the lug, so as to

prevent the removal of the tube from the 55 body of the oiler. A piston *e* is mounted in the end of the oiler, being normally urged forward by a spring *f*, and the oiler is provided with lugs *c''* for preventing the removal of the piston from it. The piston is provided 60 with a plunger *e'*, projecting outwardly and bearing against a shoulder *b''*. The oiler is provided with a pin adapted to enter an L-shaped slot *b''* in the barrel *b* for holding the oiler in position. The oiler is provided with 65 screw-threads *c'''*, by means of which a cap *h* can be attached to it, this cap being provided with a ring *h'* for convenience in operating it.

The operation of the device is very simple. 70 In order to fill it with grease, the tube *d* is drawn out to the position indicated in dotted lines in Fig. 7 and the grease placed in through the slot *d'*. The oiler is then forced into the cylindrical passage *b'*, the pin *g* being moved 75 through the slot *b''* and turned so that it will be retained in position. The spring *f* will force the pin back into the reversely-extending portion of the slot, and thus assist in holding it. This operation will force the grease 80 into the passage *a'''* and onto the bearing-surfaces of the wheel. The turning of the wheel will distribute the grease, and when it is desired to lubricate the bearing again it will be necessary merely to withdraw the oiler, fill 85 it, and replace it, as before. The wheel does not have to be removed. If it is desired to use oil instead of grease, the device can be placed with its end entering the passage *b'* and the oil poured in through the slot *d'*, as 90 before. The oil then enters the tube, and if any is spilled it goes into the passage *b'*, and the forcing of the oiler to its proper position forces the oil to the bearing-surfaces.

In the form shown in Figs. 3, 4, and 6 a 95 steel skein *A* is shown, this being provided with a depression *a''* and passage *a'''*, as described above. A collar *k* is secured to the skein, and this holds a plate *l*, which is provided with a receptacle *m*. The plate *l* is 100 also preferably riveted to the skein, as indicated. The receptacle *m* is provided with a passage *m'*, communicating with the passage *a'''* and with a bayonet-joint *B'*, similar to the joint *b''*. The plate is also provided with an 105 extension *n*, passing into the depression *a''* and extending some distance toward the end of said depression. This provides for direct-

ing the oil far enough away from the edge of the bearing, so that it may be properly discharged without waste. The receptacle has a shoulder B^3 , similar to the shoulder d^3 . It will be clear that the two devices may be operated in substantially the same manner and also that the two devices illustrated while showing the principle of our invention do not indicate all the forms in which it may be embodied.

Having thus described our invention, we claim as new and desire to secure by Letters Patent—

1. In a lubricator for wagon-axles, the combination with a skein having a passage, of a receptacle having a passage communicating with the first-mentioned passage, and a member adapted to enter said second passage for holding a lubricant therein; said receptacle having means for holding said member in the passage, and said member having means for preventing the disengagement of said first-mentioned means.

2. In a lubricator for wagon-axles, the combination with a skein having a bearing-surface provided with a depression and a passage communicating with said depression, of a receptacle having a passage communicating with said first-mentioned passage, and a member adapted to enter said second passage for holding a lubricant therein; said receptacle having means for holding said member in the passage, and said member having resilient means for preventing the disengagement of said first-mentioned means.

3. In a lubricating device, the combination with a bearing element having a depression upon a bearing-surface thereof, and a passage communicating with said depression, of a receptacle mounted adjacent to said bearing element and provided with a passage communicating with the first-mentioned passage and with a shoulder near its inner end, and a member mounted within said second passage, said member being provided with a plunger adapted to engage said shoulder, and with a spring for forcing said plunger against the shoulder, said receptacle being provided with means for locking the member in position.

4. A lubricating device comprising a receptacle having a passage for communicating with a bearing and provided with a shoulder at its inner end and a bayonet-slot at its outer end and an oiler in the receptacle and provided with a spring-pressed plunger engaging the shoulder of the receptacle and with a pin engaging the bayonet-slot of said receptacle.

5. A lubricating device comprising a hollow body, a spring-pressed plunger in the body and having on its outer face a projection extending beyond the inner end of said body, and a tube slidably mounted on said body.

6. A lubricating device comprising a body portion having a lug thereon, and a tube slidably mounted upon the outside of the body portion and provided with a slot through which said lug passes and by means of which a lubricant may be introduced into the lubricator.

7. A lubricating device comprising a movable body, and a sleeve movably mounted thereon, said sleeve having a slot for guiding it with respect to the body and for the reception of a lubricant.

8. A lubricating device comprising a hollow body open at its inner end and provided with inwardly-projecting lugs at said open end, a spring-pressed plunger in the body, and having a projection on its outer face, and a tube having sliding and guided movement on said body.

9. In a lubricating device, the combination with a bearing element having a passage, of a receptacle mounted adjacent to said bearing element and provided with a passage communicating with the first-mentioned passage and with a shoulder at its inner ends, and an oiler mounted within said second passage, said oiler having a sleeve slidably thereon and provided with a plunger having a projection adapted to engage said shoulder, and means for forcing the projection of the plunger against the shoulder.

10. In a lubricating device, the combination with a bearing element having a passage, of a receptacle mounted adjacent to said bearing element and provided with a passage communicating with the first-mentioned passage and with a shoulder at its inner end, an oiler mounted within said second passage, said oiler having a sleeve slidably thereon and provided with a plunger having a projection adapted to engage said shoulder, and means for forcing the projection of the plunger against the shoulder, and means for locking the oiler in the said passage.

In testimony whereof we have signed our names to this specification in the presence of two subscribing witnesses.
